UNITED STATES PATENT OFFICE.

THEODORE ESKILSSON, OF NEW YORK, N. Y.

AUTOMATIC CAR SAFETY SWITCH.

Application filed February 6, 1923. Serial No. 617,231.

My present invention relates to safety switches, particularly, but not exclusively, intended for use in connection with passenger elevators and like structures, and aims
5 to provide devices of the general character indicated which shall be designed to place the elevators or like structures in which such devices may be installed in an inoperative condition, in a certain and simple manner,
10 when the elevator or like structure is left without its customary attendant. A further object of the present invention is to provide devices of the general character referred to which shall be so constructed and arranged
15 to be operated as to provide readily visible means which shall serve as a reminder to the operator of the elevator or like structure of the desirability or necessity of rendering the elevator or like structure inoperative when
20 he desires or is, for some reason, compelled to leave the same. Preferably the devices of the present invention are so constructed and arranged as to automatically render the elevator or like structure inoperative upon the
25 removal of a key or other visible reminder or operating member, the removal of such key or equivalent device automatically rendering, in the desired simple and certain manner, the elevator or equivalent structure
30 inoperative, and its return or reinsertion and operation being required and acting to restore the elevator or equivalent structure to its normal operative condition.

In the following specification I shall describe, and in the annexed drawing show, an illustrative embodiment of the present invention. It is, however, to be clearly understood that my invention is not limited to the particular embodiment thereof herein shown and described for purposes of illustration only.

Referring to the drawing, wherein the aforesaid illustrative embodiment of the present invention is illustrated:

45 The single figure of the drawing shows in plan view, with the cover of the device omitted, one illustrative form of the present invention, with the operative position of the switch indicated in full lines and the inoperative position of the switch indicated in dotted lines.

50 Referring now to the aforesaid illustrative embodiment of the present invention and particularly to the drawing illustrating the same, 10 indicates the casing of the device as a whole, which may be made of composi-

tion, stone, slate or other suitable material, preferably of an insulating character, and which may be provided with a cover, which has here been omitted for the purpose of 60 making the showing clearer, which may be attached to the casing 10 by means of screws or the equivalent of fastening devices passing into the threaded or other openings 11 and 12 in the casing. The casing 10 has the ears 65 or lugs 13 and 14 provided with the threaded or other openings 15 and 16, respectively, by means of which the casing 10 and the switch parts contained therein may be suitably fastened in any desired position in the elevator 70 or other structure in which the device of the present invention is intended to be employed.

Within the casing 10 is a switch generally indicated by reference character S and comprising a panel or other base or supporting 75 member 17 mounted on one of the sides of the casing, the panel or base being preferably made of insulating material, such as insulating fibre or the like. While various types of electric switches may be employed 80 in accordance with the principles of the present invention, I prefer to use a switch of the knife blade type, since this type of switch possesses numerous advantages from the viewpoints of simplicity of construction 85 and certainty of operation for the intended purpose.

The switch S accordingly comprises a plurality of clip contacts 18 and 19 with which are associated the respective binding posts 90 or equivalent connecting devices 20 and 21. The blade 22 of the switch S is pivotally mounted about the pivot 23 between the prongs of the clip 19 in such a position that the operation of the blade 22 by means of 95 the handle 24 into the closed position of the switch, as shown in full lines in the drawing, will bridge the gap between contacts 18 and 19 and thus close the circuit so as to render the elevator or like structure operative, while the operation of the blade 22 into open position of the switch, corresponding to the position shown in dotted lines in the drawing, will render the elevator or like structure inoperative.

100 At its inner end the blade 22 is provided with an extension 25 attached to the blade 22 by any suitable fastening means, such as the screws 26. Preferably the extension 26 is angularly disposed with respect to the 110 blade 22, so as to render the operation of the switch into open or inoperative posi-

tion, corresponding to the inoperative position of the elevator or like structure in which the switch may be installed, more certain and convenient. The extension 25 is so constructed and arranged as to be operated on by a cam member 27 which is preferably of substantially semi-circular shape and is preferably made of any suitable insulating material, such as insulating fibre. The cam member 27 is attached to the tumbler 28 of a lock which is generally indicated by reference character L. The cam member 27 may be attached to the tumbler 28 by means of screws or other suitable fastening devices 29.

15 As clearly indicated in the drawing, the operation of the tumbler 28 carrying the cam member 27 from the unlocked position of the lock L, corresponding to the position of the cam member and tumbler indicated 20 in full lines in the drawing, into the locked position of the lock, corresponding to the position of the cam member and tumbler shown in dotted lines in the drawing, will serve, if the switch is in closed position, corresponding to the full lines in the drawing, to throw said switch into open position, corresponding to the dotted lines in the drawing.

For the purpose of effecting the desired 30 operation of the lock into unlocked and locked positions, corresponding to the closed and open positions of the switch, respectively, which in turn correspond to the operative and inoperative positions, respectively, 35 of the elevator or other structure in which the device may be installed, I prefer that the lock L shall be of the type known in the art as the "Yale" type of tumbler lock, provided with a key K which can be removed 40 only when the lock is in locked position, corresponding to the open position of the switch, as indicated in dotted lines in the drawing, which in turn corresponds to the inoperative position of the elevator or like structure in 45 which the device may be installed. The lock structure, which may be of any suitable sort, within the limits imposed by the functions intended to be performed by it, is not a part 50 of the present invention and need therefore not be shown here, being contained within a suitable housing 30 fastened within the casting 10 by any suitable fastening means, such as the screws or equivalent fastening devices 31.

55 The operation of the aforesaid illustrative embodiment of the present invention, and the advantages of the same in use, will be substantially clear from the foregoing description and may be briefly summarized as follows: Assuming the switch to be initially in closed position and the lock to be in unlocked or open position, corresponding to the showing in full lines in the drawing, it will be apparent that the key K cannot be removed from the lock L without operating the

lock into locked position, which will operate the switch into open position. In the position of the device first described, the key will remain in the lock as a visible reminder to the operator that the same is to be removed 70 when he leaves the elevator or equivalent structure in which the device is installed. However, as already indicated, the removal of the key cannot be effected without throwing the lock into locked position, corresponding 75 to the open position of the switch and the inoperative position of the elevator or equivalent structure. With the key removed, the switch will be securely locked in open position, corresponding to the showing in 80 dotted lines in the drawing. Nor can the switch be unlocked and operated into closed position, corresponding to the operative position of the elevator or like structure, without the reinsertion of the key into the lock and 85 the operation of the lock into unlocked position, thus releasing the switch, which may now be manually operated into closed position, corresponding to the operative position of the elevator or like structure. 90

It will be apparent that the aforesaid illustrative embodiment of the present invention is exceedingly simple in construction and may be cheaply manufactured on a basis which permits of quantity production. The 95 device is certain and safe in operation, and the location of the key is such as to serve as a constant and readily visible reminder to the operator that the key should be removed when he leaves the car. This act he cannot 100 perform without locking the switch in open position, corresponding to the inoperative position of the elevator or equivalent structure. The operation of the switch is therefore, in a sense, automatic, which commends 105 the device to underwriters and insurers of passenger elevators and like structures, and renders the device a commercially valuable and highly marketable article.

What I claim is:

1. In a safety switch for electric elevators and the like, a key-operated lock of the tumbler type, a rotatable tumbler-operated cam-supporting member, and a cam member of insulating material attached to said cam-supporting member, in combination with a rotatable switch member having an extension adapted for engagement by said cam member and adapted to be locked in open position of the switch upon operation of the lock into 115 locked position by the action of said cam member on said extension.

2. In a safety switch for electric elevators and the like, a key-operated lock of the tumbler type, a rotatable tumbler-operated cam-supporting member, and a substantially 125 semi-circular cam member of insulating material attached to said cam-supporting member, in combination with a rotatable switch member having an extension adapted for en- 130

gagement by said cam member and adapted to be locked in open position of the switch upon operation of the lock into locked position by the action of said cam member on

5 said extension.

3. In a safety switch for electric elevators and the like, a key-operated lock of the tumbler type, a rotatable tumbler-operated cam-supporting member, and a cam member of 10 insulating material attached to said cam-supporting member, in combination with a rotatable switch member of the knife-blade type having an angularly disposed extension adapted for engagement by said cam member and adapted to be locked in open position of the switch upon operation of the lock into locked position by the action of said cam member on

15 said extension.

4. In a safety switch for electric elevators and the like, a key-operated lock of the tumbler type, a rotatable tumbler-operated cam-supporting member, and a substantially semi-circular cam member of insulating material attached to said cam-supporting member, in combination with a rotatable switch member of the knife-blade type having an angularly disposed extension adapted for engagement by said cam member and adapted to be locked in open position of the switch upon operation of the lock into locked position by the action of said cam member on

20
